Primary Examiner — Kelley Donnelly(74) *Attorney, Agent, or Firm* — Buskop Law Group, PC; Wendy Buskop(57) **CLAIM**

The ornamental design for a thermo-formed plastic basket, as shown and described.

DESCRIPTION

FIG. 1 is a perspective view of the thermo-formed plastic basket.

FIG. 2 is a first side view of the thermo-formed plastic basket.

FIG. 3 is a second side view of the thermo-formed plastic basket.

FIG. 4 is a top view of the thermo-formed plastic basket.

FIG. 5 is a bottom view of the thermo-formed plastic basket; and,

FIG. 6 is a cross-sectional view of the thermo-formed plastic basket.
